WINDOW FRAME AND DOUBLE SASH UNIT

Prentice M. Henderson and Louis H. Gatter,
St. Louis, Mo.

Application March 12, 1945, Serial No. 582,192

1 Claim. (Cl. 20—49)

1

This invention relates to improvements in window units or assemblies for dwellings and buildings generally, and has particular reference to conventional rectangular forms of double sash window units of rectangular formation, as mounted within a suitable rectangular frame, and including an outer upper sash and an inner lower sash arranged to slide over one another, side by side, in the process of opening or closing the same. The present invention comprises certain additions, modifications and improvements upon two co-pending applications, one being identified by Serial Number 531,137, filed April 15, 1944, now abandoned and the other being identified by Serial Number 541,364, filed June 21, 1944, now Patent No. 2,429,054, patented October 14, 1947.

One important object of the present invention is to provide in a double sash window unit of the kind referred to and including a window frame having a horizontally extended sill, side rails seated at their lower ends upon the ends of the sill and extended vertically in parallel spaced relation, the inner faces thereof being planar, and upper cross or top members horizontally connecting the upper ends of the side rails, the said side rails being formed at each side of the frame with longitudinally extended, parallel and spaced guide grooves or channels of lesser width than the edges of the side rails of the sashes, pairs of guide, follower or brace strips of the approximate lengths of the side rails of the sashes, slidably mounted within the said guide grooves or channels of the window frame, pivotal connections between the lower ends of the said guide, follower or brace strips and the lower ends of the side rails of the sashes, and upon which pivotal connections the sashes may be tilted inwardly to approximate horizontal positions for cleaning the outer surfaces thereof, or for like purpose, the thickness of the said guide or brace strips being preferably but not necessarily slightly less than the depth of the guide grooves or channels for clearing the edges of the sashes, and means for releasably latching the sashes in their normal upright positions to the guide or brace strips, whereby the sashes and guide or brace strips may together be raised or lowered in the usual manner of sash operation.

Another object of the invention is to provide in a double-sash window unit of the kind referred to and including a rectangular window frame with rectangular sashes mounted therein side by side to slide over one another, the inner faces of the side rails of the window frame being planar and formed with parallel and spaced guide

2

grooves or channels of lesser width than the thickness of the side rails of the sashes, pairs of guide, follower or brace strips of the approximate lengths of the sashes and side rails thereof, slidably mounted within the said guide grooves or channels of the window frame, the thickness of the said guide or brace strips being preferably but not necessarily slightly less than the depth of the guide grooves or channels for clearing the edges of the sashes, the said strips being of stiff and rigid material and channeled along their outer sides as disposed in the frame for receiving the conventional sash chains or steel ribbons of such units, the said sashes and guide or brace strips being pivotally connected at their lower ends to enable the sashes to be tilted inwardly, co-acting elements upon the upper ends of the guide or brace strips and side rails of the sashes for releasably locking these elements together with the sashes in their normal upright positions, for supporting the sashes to their usual operative positions for opening or closing.

Another object of the invention is to provide, in a window and frame unit of the kind referred to above, means including structure for conveniently assembling the sashes, guide or brace strips and co-operative pivot elements, within the grooves or channels of the side rails of the frame.

With the stated objects in view, together with such other and additional objects and advantages as may be pointed out in the following specification, attention is directed to the accompanying drawing as exemplifying a preferred embodiment of the invention, and wherein:

Figure 1 is a horizontal cross section through one side rail of the upper, outer sash of a window unit of the kind described and the inclosing window frame, the upper rail of the inner, lower sash being shown in full lines, the side rails of the frame being shown as channeled and with guide or brace strips mounted therein, from the upper ends of which strips pivotally connected latches are shown as engaging and seated within complementary receptacles therefor formed in the upper side of said upper rail of the inner, lower sash.

Figure 2 is a vertical section on a plane indicated by the line 2—2 of Figure 1.

Figure 3 is a fragmental, perspective view, on an enlarged scale, of a lower section of a window frame and sash unit of the kind referred to, showing the lateral portions of the lower and inner sash as mounted within the frame of which the side rail at one side is shown, showing the man-

ner of channeling the side rails for receiving the guide or brace strips for supporting the sashes, with releasable latches pivotally connected at the upper ends of these strips for seating within complementary recesses or receptacles formed in the upper side of the top rail of the lower, inner sash.

Figure 4 is a fragmental, sectional detail, illustrating the structure of the elements involved and method of mounting and assembling the elements upon the side rails of the sashes for pivotally engaging the lower ends of the said guide or brace strips.

The drawing represents a window unit or assembly referred to generally at 5, the same being of the conventional elongated and rectangular form, and including the sill pieces 6, side rails 7 seated upon the ends of the sill, and the usual upper cross members (not here shown) for connecting the upper ends of the side rails of the frame.

It is to be noted that in applying this invention to the described form of window unit, the inner faces of the side rails 7 are planar in finish, the usual inner guide strips for the lower, inner sash being omitted, as well as the usual medial parting strips for defining the guide-ways of such conventional window unit. However the outer guide strips 8 may be retained if desired, since in either case and whether retained or omitted, these outer guide strips are not involved in this present invention. These said inner faces of the side rails 7 are grooved or channelled longitudinally in transverse alignment at each side of the frame with parallel, spaced and aligned guide grooves or channels 9, these grooves being preferably of lesser width than the thickness of the side rails of the sashes as mounted within the frame 5. These sashes include an inner, lower sash 10, and an outer, upper sash 11, assembled in conventional manner side by side within the frame 5 and adapted to slide over one another in the process of opening or closing the said sashes.

In accordance with this invention, follower or brace strips 12, of the approximate lengths of the side rails of the sashes, are slidably mounted within the grooves or channels 9 of the side rails 7 of the window frame, the thickness of these strips being preferably but not necessarily slightly less than the depth of the guide grooves or channels so as to clear the lateral edges of the sashes in the operation of the invention and in tilting the sashes inwardly from the window frame. The brace strips 12 are to be made of rigid and stiff material, metal or otherwise as desired, and are channelled along their outer sides as disposed in the window frame, for conveniently receiving the conventional sash chains or flexible steel ribbons 13 which at their inner ends are riveted as at 14 to the upper ends of the brace strips 12. These chains or ribbons are extended upwardly over pulleys journaled in the upper ends of the side rails 7 of the window frame, the outer ends thereof being then depended through wells formed in the frame and connected to sash weights, all in conventional manner and not here shown. The lower, lateral corners of the sashes 10 and 11 are recessed or chambered out as indicated at 15, and pivot-bolt bores 16 are extended laterally outward therefrom in the planes of the sashes and opening into the grooves or channels 9 of the rails 7 of the frame. Pivot bolts 17 are slidably passed through the bores 16, and at their outer ends are adapted to slide into aligned holes 18 formed through the lower ends of the brace

strips 12, all as illustrated in detail in Figure 4. The recesses 15 are preferably cut upwardly into the ends of the lower horizontal rails of the sashes 10 and 11, and with the sashes removed from the window frame the bolts 17 are inserted through the bores 16, fully inward and so that the outer ends of these bolts will fall flush with the edges of the sashes. The sashes are then positioned properly within the window frame, with the lower margins of the sashes aligned with the lower ends of the brace strips 12, and the bolts 17 are then pushed outwardly through the holes 18 formed as aforesaid in the lower ends of the strips. The bolts 17 may be fixedly secured in place in operative position by means of nails 19 passed through the apertured inner ends of the bolts and into the body portions of the lower rails of the sashes, as shown in Fig. 4. Metal reinforcing strips 20 may be secured by screws 21 to the lateral edges of the lower ends of the sashes and apertured in alignment with the holes 18 and bores 16, for passing the bolts 17 and for supporting said bolts in the operation of the sashes, thus relieving from wear the conventional wooden rails of the sashes.

Elongated latches, channelled and U-shaped in cross-section, and here indicated at 22, are pivotally pinned as at 23 to the upper ends of the brace strips 12, for which purpose the medial webs of these strips are cut away at their ends, as indicated in Figure 3. The upper horizontal faces of the upper cross rails of the sashes 10 and 11 are grooved or channelled out as shown at 24, in the plane of the sashes, to provide elongated sockets adapted to receive and seat the latches 22 when the latter are turned inwardly and down into said sockets. These latches are preferably mounted as shown, with their channelled sides turned downwardly, when entered into their sockets 24. In Figure 3 the latch at the left hand side of the sash is shown as turned down into its socket, while at the right hand side the latch is shown as raised and elevated from the socket. In order to facilitate the operation of these latches, the sockets 24 are enlarged at their ends as shown at 24a, so that the operator's finger may be inserted therein for lifting the latches. The sockets 24 are also formed with the laterally off-set notches 24b for engaging the studs 22a which are rigidly and laterally extended from the latches 22, and thus when these latches are turned down into the sockets they function to effectively lock the upper ends of the sashes to the guide or brace strips, the lower ends of the sashes being supported as already pointed out, by means of the pivot bolts 17 as entered through the holes 18 of the strips 12. If desired the sockets 24 may be lined with metal liners in conventional manner, and not here shown.

At the upper ends of the sashes 10 and 11, when these sashes are both in their lowered positions, the grooves or channels 9, as formed as aforesaid in the side rails 7 of the window frame, are chambered or mortised out laterally at one side of said channels, so as to provide somewhat elongated and laterally off-set rectangular recesses 9a, disposed in planar alignment with the studs 22a of the latches 22. Oblong metal housings 25 are provided and nicely fitted and secured within the recesses 9a, these housings being open on their sides adjacent the channels or grooves 9, as indicated at 25a, and otherwise closed except for the narrow openings 25b formed through the lower ends of the outer sides of the housings, 75 and through which openings the studs 22a of the

latches 22 may enter into the housings as the latches are raised up or elevated in the operation of the invention in manner later pointed out.

It is to be noted that the housings 25 of the inner channels 9, for the inner and lower sash 10, are so disposed and upwardly spaced in transverse alignment within said channels, that when the inner and lower sash 10 is lowered into contact with the window sill 6, the latches 22 at each side of this sash may be raised or turned upward and the studs 22a of these latches will then exactly align with and enter into the housings through the narrow openings 25b, and it is to be noted that the sash 10 may then be raised slightly to the extent of the length of the housings 25, for enabling the sash to clear the top of the sill 6 as the sash is tilted inwardly. The releasing of the latches 22 of course enables the sash to be thus tilted inwardly, as there is no other impediment to this action. The sash will then lie approximately horizontally across the sill, and will be held in that position by the lugs or studs 22a, which impinge against the upper ends of the housings 25 and prevent further upward movement of the lower end of the sash.

Similarly, the housings 25 of the outer channels 9, for the outer and upper sash 11, are disposed somewhat above the housings as just described for the inner and lower sash 10, so that when this sash 11 is lowered in turn after the lowering and inward tilting of the sash 10, and the latches 22 of the sash 11 are raised, the studs 22a of the sash 11 will pass into the housings 25 of the outer channels, and the sash 11 may then also be tilted inward, over and upon the sash 10, where it will similarly lie horizontally supported for cleaning or the like.

It is thought that from the foregoing description, taken with reference to the drawing, the construction, mode of operation and use of the invention will be fully understood, and while a specific embodiment of the invention is here shown and described, the structural features as shown may be changed or modified in minor particulars as may be desired, within the scope however of the appended claim.

We claim:

In a window frame and sash unit of the kind described and including a sill having its inner ledge raised above the outer ledge, and there being spaced side rails extended vertically at the ends of the sill in transverse, parallel alignment

and formed with guide channels longitudinally extended along their inner sides, and including a window sash slidably mounted within the frame with the lateral edges of the sash aligned over 5 the guide channels of the side rails, and including brace strips slidably mounted within the guide channels of the side rails and of the approximate length of the sash, and there being pivotal connections between the lower ends of the brace strips at each side and the side rails of the sash, whereon the sash may be tilted inwardly, latches hinged to the upper ends of the brace strips and arranged to turn down into sockets as formed in the upper horizontal faces of the upper cross rail of the sash for locking the sash to its normal, vertical and operative position in the frame, the said latches however being adapted to turn upwardly from the sash and vertically into the guide channels of the side rails of the frame, and being provided with laterally extended studs, 10 there being recesses formed and extended laterally at one side of the guide channels of the side rails, elongated metal housings mounted within said recesses, the same being closed on 15 all sides except the sides facing and opening into the guide channels of the side rails of the frame, and except for inwardly opening cut-outs for receiving the said laterally extended studs of the latches as mounted on the sash with the latter 20 being provided with laterally extended studs of the sash in lowered position in the frame, whereby the studs may enter into the housing as the latches are raised, and the sashes then be turned down horizontally inward over the raised inner ledge of the sill, the length of the housing permitting 25 the lower end of the sash to travel upwardly relative thereto for flatly positioning the sash across the sill.

PRENTICE M. HENDERSON.
